US00D725666S

(12) **United States Design Patent**
Tseng et al.

(10) **Patent No.:** **US D725,666 S**
(45) **Date of Patent:** **** Mar. 31, 2015**

(54) **DISPLAY SCREEN WITH GRAPHICAL USER INTERFACE**

(71) Applicants: **Erick Tseng**, San Francisco, CA (US); **Yoon Kean Wong**, Redwood City, CA (US); **Colin Cameron Brennan Campbell**, San Francisco, CA (US); **Brian Krausz**, Mountain View, CA (US); **Matthew Nicholas Papakipos**, Palo Alto, CA (US)

(72) Inventors: **Erick Tseng**, San Francisco, CA (US); **Yoon Kean Wong**, Redwood City, CA (US); **Colin Cameron Brennan Campbell**, San Francisco, CA (US); **Brian Krausz**, Mountain View, CA (US); **Matthew Nicholas Papakipos**, Palo Alto, CA (US)

(73) Assignee: **Facebook, Inc.**, Menlo Park, CA (US)

(**) Term: **14 Years**

(21) Appl. No.: **29/450,205**

(22) Filed: **Mar. 15, 2013**

(51) LOC (10) Cl. **14-04**

(52) U.S. Cl.

USPC **D14/486**

(57) **CLAIM**

The ornamental design for a display screen with graphical user interface, as shown and described.

DESCRIPTION

The FIGURE is a front view of a display screen with graphical user interface showing the new design.

The broken lines illustrating the display screen, mobile device, and portions of the graphical user interface form no part of the claimed design.

1 Claim, 1 Drawing Sheet
